US00D628202S

(12) **United States Design Patent**
Pomerantz et al.

(10) **Patent No.:** **US D628,202 S**
(45) **Date of Patent:** **** Nov. 30, 2010**

(54) **MICROSD MEMORY CARD WITH
DIFFERENT COLOR SURFACES**

(75) Inventors: **Itzhak Pomerantz**, Kefar Sava (IL);
Robert C. Miller, San Jose, CA (US)

(73) Assignee: **SanDisk Corporation**, Milpitas, CA
(US)

(**) Term: **14 Years**

(21) Appl. No.: **29/359,213**

(22) Filed: **Apr. 7, 2010**

CLAIM

The ornamental design for a microSD memory card with different color surfaces, substantially as shown and described.

DESCRIPTION

FIG. 1 is a front perspective view of a microSD memory card with different color surfaces according to a first embodiment of our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof;

FIG. 7 is a front elevation view thereof;

FIG. 8 is a front perspective view of a microSD memory card with different color surfaces according to a second embodiment of our new design;

FIG. 9 is a top plan view thereof;

FIG. 10 is a bottom plan view thereof;

FIG. 11 is a left side elevation view thereof;

FIG. 12 is a right side elevation view thereof;

FIG. 13 is a rear elevation view thereof;

FIG. 14 is a front elevation view thereof;

FIG. 15 is a front perspective view of a microSD memory card with different color surfaces according to a third embodiment of our new design;

FIG. 16 is a top plan view thereof;

FIG. 17 is a bottom plan view thereof;

FIG. 18 is a left side elevation view thereof;

FIG. 19 is a right side elevation view thereof;

FIG. 20 is a rear elevation view thereof;

FIG. 21 is a front elevation view thereof;

FIG. 22 is a front perspective view of a microSD memory card with different color surfaces according to a fourth embodiment of our new design;

FIG. 23 is a top plan view thereof;

FIG. 24 is a bottom plan view thereof;

FIG. 25 is a left side elevation view thereof;

FIG. 26 is a right side elevation view thereof;

FIG. 27 is a rear elevation view thereof; and,

FIG. 28 is a front elevation view thereof.

The differently-shaded areas indicate different color surfaces of the microSD memory card but are not intended to indicate specific colors. However, the white unshaded areas depict the color white.
